[57] **CLAIM**

The ornamental design for a distribution head for particulate material, as shown.

DESCRIPTION

FIG. 1 is a perspective view of a distribution head for particulate material showing our new design;

FIG. 2 is a elevational view thereof, showing one of two identical views;

FIG. 3 is a top plan view;

FIG. 4 is a front elevational view;

FIG. 5 is a rear elevational view; and

FIG. 6 is a bottom plan view thereof.
